UNITED STATES PATENT OFFICE.

JOSHUA W. SYKES, OF DETROIT, MICHIGAN.

DESIGN FOR A COMMUNION-SERVICE TRAY.

SPECIFICATION forming part of Design No. 26,061, dated September 22, 1896.

Application filed June 20, 1896. Serial No. 596,348. Term of patent 14 years.

To all whom it may concern:

Be it known that I, JOSHUA W. SYKES, a citizen of the United States, residing at Detroit, in the county of Wayne and State of Michigan, have invented and produced a certain new and original Design for a Communion-Service Tray; and I do hereby declare the following to be a description thereof, reference being had to the accompanying drawings, forming a part of this specification.

Figure 1 is a general perspective view of a service-tray, showing my design; and Fig. 2 is a vertical section therethrough, these two views being deemed sufficient to fully illustrate my design.

The leading feature of my design consists in a tray having a flaring rim extending beyond the tiers arranged in the form of a pyramid, which extend upward therefrom, the topmost tier being provided with a suitable handle, said handle representing a cup or other vessel.

A represents the tray proper, which is provided with a suitable upturned rim A', by means of which said tray may be conveniently handled in passing it from one person to another.

Rising from the tray is a series of tiers or elevations B C D, each successive tier being enough smaller than the one from which it

rises to permit of the small apertures b c d, into which suitable cups or wine-receptacles may be seated. Mounted upon the topmost tier D is a suitable base E, and formed integral with said base is a neck e, from which project the bifurcated portions F. In the upper ends of the bifurcations F is a spindle f, and surrounding said spindle is a suitable handle.

It will be seen by reference to the views, especially Fig. 2, that the general contour of the handle, comprised of the bifurcations F, neck e, and base E, resembles that of a cup.

The sides of the portions F may be decorated, as by the addition thereto of grapes or other fruits, symbolical of the wine which the tray is designed to serve. The edges of the tiers B C D, as well as the rim A', may be beaded to represent grapes or decorated to correspond with the decoration of the handle.

What I claim is—

The design for a communion-service tray, substantially as herein shown and described.

In testimony whereof I affix my signature in presence of two witnesses.

JOSHUA W. SYKES.
